ELECTRIC MOTOR

John A. Hanley, Stamford, Conn., assignor, by
mesne assignments, to Clipshave Inc., a cor-
poration of New York

Application December 17, 1934, Serial No. 757,755

25 Claims.

(Cl. 172—36)

My present invention relates to compact, low-power electric motors of the type used for driving small tools such as apparatus for shaving, hair-clipping, massaging or the like, and more especially of the type in which the motor is encased or housed within the handle of the tool.

An object of the invention is to provide an apparatus of the above type, rugged, compact and inexpensive in construction, which shall be of universal utility, both on direct and on alternating current circuits.

Another object is to provide an apparatus of the above type, which can be readily started by a simple manipulation, with the same hand that grasps the apparatus, and in which no exposed part revolves while the motor is running.

Another object is to provide an apparatus of the above type which has a minimum amount of winding, a minimum number of circuit connections and which is not subject to short circuit or shock to the operator.

Another object is to provide an apparatus of the above type which is subject neither to excessive heating nor to excessive sparking in the course of operation, all without resort to exposed metallic cooling surfaces, magnetic blowouts, condensers or other special spark extinguishing accessories.

Another object is to provide apparatus of the above type, the small casing of which is substantially completely filled by the largest motor capable of being accommodated therein and which motor is so designed as to admit of an armature practically the full width of the casing.

Another object is to provide a motor of the above type, of simple stampings easily assembled, said motor of low power consumption, yet exerting substantial operating force on the tool, not easily stalled, smooth in operation and inherently non-hunting, in the absence of any adjustment devices to that end.

A feature of the invention is the use of an armature rotor operating between the poles of a field stator, both enclosed within an insulating handle casing, there being a contact breaker operated by a cam conformation on the armature shaft and in circuit with the electromagnetic winding of the motor.

Another feature is the rotary armature, having three or more poles for efficient operation, with its transverse diameter beyond the two field poles and therefore of diameter substantially equal to the maximum width of the field.

Another feature is the arrangement whereby each pole of the field structure is made of a

distinct set of L-shaped laminations, the bases of which are frictionally fitted from opposite ends of an insulating spool for the field coil, which thus carries the laminations.

Another feature is the construction of the field coil in two segments with an intervening insulating plate to cause said coil to have substantial capacity effects, tending to preclude any arc at the breaker contacts; also to facilitate starting under direct current operation by neutralizing the choking effect of the coil, and furthermore to reduce the likelihood of arcing across the insulation of the coil.

Another feature is the transmission for operating the tool by a lever protruding from the casing, pivoted preferably to the rotor frame and caused to oscillate by an eccentric at one end of the rotor shaft.

Another feature is the mode of mounting the motor within the casing by fit of the field between the lateral walls of the casing and mounting of the armature frame upon bosses molded in the floor of the casing and affording space for the transmission lever.

Another feature is the disposition of the contact breaker upon the armature frame and the disposition of the breaker points in the space between the armature and the field winding.

Another feature is the connection of the breaker elements in circuit with the stationary field by flexible exposed leads accommodating the relative movement and serving as heat radiating fins.

Another feature is the use of a starting roller protruding from the casing, normally free from contact with the rotor and brought into peripheral engagement therewith in the application of the starting torque, said roller remaining inactive while the motor is running.

Another feature is the construction of the rotor or armature with non-magnetic segments intervening between the poles of one or more magnetic laminations to afford continuous uninterrupted engagement for the starting roller during the application of the starting torque, without reducing the magnetic effect of the rotor.

In the accompanying drawing, in which is shown one of various possible embodiments of the several features of the invention,

Fig. 1 is a plan view of the apparatus with the cover removed, showing the contact breaker just closed.

Fig. 2 is a view in longitudinal cross-section on line 2—2 of Fig. 1.

Fig. 3 is a fragmentary plan view similar to

Fig. 1, showing the contact breaker about to open, 5

Fig. 4 is a perspective view of the armature, 5

Fig. 5 is a detail view on a larger scale taken 10 on the line 5-5 of Fig. 3, and

5 Fig. 6 is a fragmentary side elevation, showing the arrangement of the starting roller.

Referring now to the drawing, the device includes a casing 10 preferably molded of "Bakelite", vulcanite or similar composition with special conformations to house the motor and parts now to be described. In particular the casing includes side walls 11 and 12 between which are snugly fitted the legs 13 of the laminated motor field, which is preferably of the two-pole type.

15 Preferably the field coil is prewound on a unitary open insulating frame or spool F of "Bakelite", vulcanite or the like, said frame being preferably rectangular and having flanges 81 and 82 at its ends. The coils 15 and 16 are wound about 20 said frame in contact with the respective flanges and at their contiguous ends they contact a separating median fin 93 which is an integral part of and completely encircles the spool F.

The outer terminals of coils 15 and 16 are connected 25 respectively to binding posts 17 and 18 on the tops of reinforced ribs 19 at the corners of the casing and are electrically connected to leads 19 and 20 protruding at 21 from the rear of the casing through insulating bushing 22.

30 Unlike conventional U-field constructions in which the field coil is wound about and carried by the field structure, the field laminations are carried by the coil spool unit. To render possible such assembly the U-shaped field is not made 35 of U-shaped laminations but each lamination is made of two symmetrical L-shaped parts 13. Two stacks of laminations are inserted through opposite ends of the spool F to snugly fit and completely to fill the opening thereof, as best 40 shown in Fig. 1, with the ends of said laminations in abutting relation at 84 to form the yoke of the field. In operation of the motor, as is obvious, the abutting ends of the field laminations are magnetically drawn together. Fastening 45 screws 82 through the field stack and preferably near the poles, bind the field structure firmly against a shelf (not shown) in the floor of the casing.

The armature is a rotor unit comprising preferably 50 a stack of laminations 23 having arcuate notches 24 therein to form three poles P', P² and P³. The stack of laminations is secured together by pins 25 transversely through the poles thereof. The three-pole construction of armature makes for a far smoother operation than a two-pole armature, since the torque impulses are more frequent and a relatively shorter mean magnetic path is afforded.

For application of starting torque in manner to 60 be set forth below, one of the magnetic iron armature segments 23' preferably near the top of the armature, has stamped thereout of key-way conformations 86, but is otherwise identical with the other laminations and does not present any 65 interruption at the pole segments.

These key slots serve to mount stiff non-magnetic segments 26, preferably of "Bakelite" impregnated fiber, having complementary keys 87 firmly fitting the respective key-ways, and if desired also cemented in place. The segments 26 occupy the gap between the successive poles of the keyed lamination 23' so that the composite lamination presents in contour a complete circle coaxial with the armature.

The effectiveness of the armature from an electromagnetic standpoint is in no way impaired by the presence of the non-magnetic segments 26, since the magnetic structure is continuous both axially and transversely and of the same 5 width and thickness throughout.

The armature has a shaft 27 tightly fitting into corresponding central holes in the laminations and having its bearings in an armature carrying frame, the latter composed of a base 10 plate 28 and a cover plate 29 both of duralumin or the like. The plates 28 and 29 have preferably in-turned apertures as at 30 and 31 extending into the corresponding central openings 30' and 31' in the uppermost and lowermost laminations of the armature and affording long and effective bearing surfaces for shaft 27. The two plates of the frame are connected together by screws 32 encircled by spacer sleeves 33 affording a cage 15 for the rotor. The rotor unit just described is 20 affixed into the casing upon upstanding bosses 34' and 34² molded as unitary parts of the floor 19 of the casing into which are threaded respectively the lower ends of screws 36 and 32 of the armature carrying frame just described. An additional boss 34³ is disposed immediately in front of the field coils 15 and 16, the base plate 28 of the motor frame being elongated as at 28' to overlap said boss, to which it is also attached by a short screw 35, readily accessible from between the legs of the motor field.

As shown in the drawing, the armature diameter transversely of the casing extends somewhat beyond the extremities of the field poles which are rounded as at 13' to accommodate the curvature of the armature. Unlike arrangements in which the field poles are in direct facing relation to accommodate the armature therebetween, the present arrangement admits of an armature of 35 diameter not materially less than the maximum width of the field structure and in turn substantially equal to the effective width of the casing. The motor therefore substantially completely fills the small handle casing without waste space 40 and is thus of largest possible size and power to be accommodated within a casing sufficiently small to be grasped as a handle.

By the arrangement described, the motor frame is spaced by the height of the bosses 34', 34² and 34³ from the floor of the casing, said space 50 serving to accommodate the transmission lever 36 by means of which the tool, illustratively a hair clipping head 37, is operated from the motor. The inner end of the transmission lever is pivoted about a screw 38 threaded into the base 28 of the armature frame and the lower end of the rotor shaft 27 has an eccentric conformation 39 extending into a slot 40 in the transmission lever, thereby to cause the latter to make one oscillation back and forth about the pivot pin 38 for each complete revolution of the motor armature. The eccentric 39 need be but slightly offset to operate the corresponding part of the lever through a relatively small path, in order to produce an effective displacement at the operating tool 37 by the multiplying effect of the long lever arm. The transmission lever as shown, has a double bend 41-42, to offset its outer tool carrying end 43 to position centrally of the front of 70 the casing.

Upon the upper plate 28 of the motor frame is mounted the contact breaker C now to be described. This breaker comprises a pair of arms 45 and 46. Arm 45 comprises a rigid bar of in- 75

sulation affixed by screw 47 to the plate 29, said bar having molded therein a conducting blade 49 carrying a contact point 50 preferably of the alloy commonly employed for ignition contact breakers. The complementary movable contact point 51 is mounted on a similar metal blade 52 similarly molded in a rigid insulating mounting arm 46 which has a rocking mount about a pivot screw 53 in the top plate 29 of the rotor casing. A blade of spring steel 54 affixed at an eye 55 thereof by means of screw 56 to the top of the rotor frame urges the arm 46 about its pivot 53 for normal engagement of the contacts 50 and 51.

The blades 49 and 52, preferably of Monel metal or other suitable alloy have their ends bent downward at right angles as at 58 into the space between the armature and the field coils and between the legs of the field, the contacts 51 and 52 extending in vertical planes as shown in Figs. 1 and 2.

The field coils 15 and 16 are series-connected through the contacts 50 and 51 by means of wire leads 64 retained by wire holding clips 60 and 61 of fiber, each secured to the field by the screw 62, which holds the field in place. Each wire clip has an upstanding eye 63 mounting the corresponding insulated lead 64 from the field coil. Soldered to the protruding end 65 of each lead is a corresponding flexible connector 66, the free end of which is clamped between the associated contact point 51 and its mounting blade 52 as at 67 in Fig. 5. Connectors 66 are preferably of beryllium copper alloy and serve the purpose of a flexible connection to admit of relative movement of contacts C, and also serve as heat radiating fins to prevent overheating at contacts C.

The contact breaker is operated preferably by a triangular cam conformation 70 at the upper end of the armature shaft which clears the fixed contact arm 45 but engages the movable contact arm 46, so that in the revolution of the rotor, arm 46 is moved about its pivot 53 to break contact three times in each revolution of the armature shaft. The spring 54 in each case closes the contact as the flat side of the cam comes into engagement with the contact arm. The alternate movement of opening and closing the contact breaker will be apparent from Figs. 1 and 3.

It will be seen that the respective apices of the cam 70 register with the respective poles P', P² and P³ of the armature, so that the contact is closed when one of the armature poles is midway between the field poles, but is open when two of the armature poles are aligned with the corresponding field poles.

Once the motor has been started, the opening of the contact breakers interrupts the circuit, but the inertia of the moving armature carries it on to a position where the contact breaker again closes the circuit for further impulse, three cycles of alternate impulse and inertia advance occurring for each complete turn of the rotor. The rotation of the motor is thus uninterrupted and operation will occur regardless whether on direct current or any frequency of alternating current.

Preferably the cam is so proportioned that the circuit is alternately closed for 52 degrees and open for 68 degrees, there being thus three complete cycles of opening and closing for each rotation of the armature. In the position of Fig. 1, and assuming the rotor to turn clockwise, the circuit has just been closed and will open after a rotation of 52 degrees past the position shown. The rotor which prior to said contact closure is still moving under inertia, is given a sharp torque

due to the magnetic attraction of armature pole P' by the field pole immediately in advance of it and of armature pole P² by the field pole immediately in advance of it.

Each time contacts 50-51 open, in the operation of the motor, arcing therebetween is effectively prevented, since the residual energy in the circuit is stored as a charge, due to the capacity effect of the coil unit, coils 15 and 16 acting as the plates of a condenser in their correlation with the intervening insulating fin 93 which serves as the dielectric thereof. The stored charge is given up when the contacts are again closed, thereby adding to that extent to the effective torque of the motor. Of course the capacity effect depends upon the thickness and material of the fin 93. While the construction and arrangement of coils 15 and 16 to serve as an effective capacitor has special utility in the specific environment set forth, this feature is of more general applicability in other relations.

By the arrangement set forth, the maximum voltage existing between the ends of the field coil structure is at no time exerted on any part of the insulating carrying structure, but since the coil is in two segments separated by insulation, at most half of the maximum voltage exists across any insulating portion, so that the likelihood of arcing through the insulation is considerably diminished.

The arrangement of field coil to exert a capacity effect, aside from its advantage in preventing destructive arcing and in adding to the torque of the motor, is especially helpful in facilitating the starting of the motor on direct current, for in that relation the choking effect of the field coil is partly or wholly neutralized by its capacity effect.

It will, of course, be understood that the principle of the motor set forth could be carried out in a wide variety of manners, and that the precise construction shown and described, while preferred, is largely illustrative.

The casing, preferably has an obliquely extending upper rim 75 which at the right end is only half the height of the assembled casing, the casing cover 76 being correspondingly wider at its rear end 77 and narrower at its forward end 78. Between registering notches 79 and 80 in the cover and casing respectively, the shank 50 of bushing 22 is lodged, the cover and casing being also respectively undercut at 81 and 82 to lodge the bushing flange 83. The cover is secured to the casing preferably by screws 84, 85 and 86.

The motor is equipped with a starting appliance comprising a small insulating starting roller 87 protruding through a corresponding notch 88 at the upper rim of the casing. The notch 88 is of width less than the diameter of the roller, as shown, so that the roller is effectively held from dropping out of the casing, though no positive securing means is provided therefor. The roller is prevented from dropping into the casing by being blocked, as best shown in Fig. 1, between the casing wall, the armature and the spacer sleeve about screw 56.

The lower rim of the casing cover 76 exerts a slight longitudinal pressure on the roller, which protrudes laterally from the port in the casing 70 defined by notch 88 and the cover. The roller is substantially in the same plane as the starting segment 26 of the armature, but as best shown in Fig. 1, is normally slightly spaced therefrom.

To start the motor after plugging in the leads 21, the starting roller 87 is merely twirled with the thumb of the same hand holding the casing, which causes the roller to be pressed slightly 5 inward away from the casing wall to engage the starting segment 26 and then to start spinning the rotor, which promptly falls in step and rotates continuously in the manner above described to oscillate the transmission lever 36 and tool 37 10 at the exposed end of the casing. When the finger pressure is released from the starting roller 87, the rapidly revolving armature segment 26 kicks the roller 87 outward so that it becomes lodged in the notch 88 and is retained by the 15 slight frictional hold thereon exerted by the casing cover 76. The starting roller therefore remains stationary during the operation of the motor and the danger of injury to the user, as for instance by the catching of hair under a 20 rapidly spinning exposed part is precluded.

The starting appliance is thus of extremely simple construction, the starting roller in the assembling operation being simply dropped into place without any clutch, bearing or other holding 25 appliance therefor.

As previously indicated there are three distinct torque impulses applied at uniform intervals for each complete rotation of the armature, which 30 rotation, however, effects only one complete back and forth reciprocation of the tool 37, such as the hair clipping tool. The torque impulses being thus at intervals much more frequent than those at which the tool takes its maximum load, the motor applies full momentum to its load, and 35 the operation is therefore quite smooth and is inherently non-hunting, and the adjustment devices generally used for such purpose are dispensed with.

The power consumption of the motor is 10 40 watts or less, and while the torque on the armature is small, yet said torque is most efficiently applied.

It will thus be seen that there is herein described apparatus in which the several features 45 of this invention are embodied, and which apparatus in its action attains the various objects of the invention and is well suited to meet the requirements of practical use.

As many changes could be made in the above 50 construction, and many apparently widely different embodiments of this invention could be made without departing from the scope thereof, it is intended that all matter contained in the above description or shown in the accompanying 55 drawing shall be interpreted as illustrative and not in a limiting sense.

Having thus described my invention, what I 60 claim as new and desire to secure by Letters Patent, is:

1. An implement comprising a handle casing substantially closed at the forward end thereof and having an electric motor therein comprising a stator and a rotor, said rotor having a shaft with an eccentric at its end, and a pivoted lever 65 coacting with said eccentric and protruding through a corresponding small opening in the forward end of the casing for reciprocating a tool applied over the forward end of said casing and of area much larger than said opening and a 70 cover abutting at its forward end the rear edge of the substantially closed forward end of said casing.

2. A small, electrically operated implement 75 comprising a handle casing substantially closed at the forward end thereof and, an electric mo-

tor therein, said motor comprising a stator and a rotor, said rotor having a shaft, an eccentric integral with said shaft, a lever pivoted at one end with respect to the casing and having an aperture near said end coacting with said eccentric, the forward end of said lever protruding through a corresponding small opening in the forward end of said casing for coaction with a tool applied over the forward end of said casing and of area much larger than said opening to be reciprocated by said lever in the operation of the motor and a cover abutting at its forward end the rear edge of the substantially closed forward end of said casing. 5

3. A universal electric motor comprising a 15 field yoke having poles, a field coil thereon, a contact breaker in circuit with said field coil, a rotary armature disposed between said poles, a cage therefor said armature having a cam thereon, with as many protrusions as the armature 20 has poles, for periodically operating said contact breaker, said armature being segmental for periodic variation of the air gaps between the field poles in the rotation of the armature, the contact breaker being constructed and arranged 25 for opening and closing the field circuit at definite phases in the rotation of the armature and carrying arms for the contact breaker mounted on said cage, the contact elements of the contact breaker being lodged in the space between said 30 field yoke and said armature.

4. A universal motor comprising a field yoke having poles, an armature pivotally mounted between said poles and having a cage, said armature having poles of width nearly that of the field 35 poles and with gaps therebetween and a contact breaker in circuit with the field coil having arms mounted on said cage and operated from the armature to be opened each time two armature poles pass substantially beyond a position of registry with the field poles the contacts of said contact breaker being lodged in the space between said field yoke and said armature. 40

5. An apparatus of the character described comprising a handle casing, a universal electric 45 motor enclosed in said casing, said motor comprising a two-pole field mounted in said casing and extending longitudinally thereof and having a field coil thereabout, an armature having a rotary shaft, bearings for said shaft, a carrying 50 frame for said bearings and straddling said armature, said armature having three spaced poles 120 degrees apart, a contact breaker in circuit with said field, said breaker comprising a fixed contact and a coacting movable contact, 55 an arm carrying the latter contact and pivoted to said armature frame, a spring urging said arm to contact closing position and a cam formation on the end of the armature shaft coacting with said arm, periodically to separate the breaker 60 contacts, the parts being constructed and arranged for alternative closing of the circuit for about 52 degrees and opening of the circuit for about 68 degrees of the rotation of the armature.

6. An apparatus of the character described, 65 comprising an insulating casing constituting a handle, a universal electric motor therein, said motor having a two-pole field structure extending longitudinally of said casing and secured therein, an armature rotor unit comprising a support 70 frame having a base fixed to said casing, said base having a bearing for said rotor, said frame also having a cover piece for said rotor, a contact breaker in circuit with the field coil and carried by said frame cover piece, said armature shaft 75

having a cam formation for effecting periodic opening and closing of said contact breaker in the rotation of said armature.

7. An apparatus of the character described comprising an insulating casing having a floor with integral mounting boss support means, a two-pole field structure having an encircling coil, said field structure secured between the sides of said casing with its coil extending back of said support means, a rotary armature between the poles of said field structure, said armature including a supporting frame secured to said support means and spaced thereby from said floor, an operating lever pivoted to said frame support and 15 extending in the space determined therebelow by said support means, and an eccentric on the end of said armature shaft cooperating with said lever to oscillate the same in the rotation of said armature, the forward end of said lever being exposed 20 through the casing for operating a tool.

8. An automatic tool comprising a handle having an electric motor incorporated therein, said motor comprising a stator and a rotor, one of said elements having an electro-magnetic coil, 25 means constituting a bearing mount for said rotor, spaced from the corresponding walls of said casing, operating conformations at the opposite ends of the rotor shaft, a contact breaker in said casing coacting with one of said conformations and in circuit with said coil, and a lever 30 in said casing, cooperating with the conformation at the other end of said rotor shaft to be oscillated thereby, said lever having its free end exposed through the forward end of the casing for coaction with a tool.

9. Apparatus of the character described comprising an insulating casing, a two-pole field structure extending longitudinally of, tightly fitted in engagement with the sides of said casing, 40 and secured to the floor thereof, a coil about the end of said field structure, support boss means rising from the floor of said casing in advance of said coil, an armature unit comprising a rigid support frame and a rotor having its bearings in 45 said frame, the bottom of said support frame secured to the top of said support means, thereby spacing said frame from the floor of said casing, an operating lever pivoted within said casing and under the base of said frame, and an eccentric at 50 the lower end of the armature shaft cooperating with said lever, the forward end of said lever protruding through the front of said casing.

10. Apparatus of the character described, comprising an insulating casing, a two-pole field structure extending longitudinally of, fitted in engagement with the sides of said casing and secured to the floor thereof, a coil about the end of said field structure, boss means rising from the floor of said casing in advance of said coil, an armature unit comprising a rigid support frame and a rotor having its bearings therein, the bottom of said support frame extending beyond said 60 rotor and secured at more than one point to said boss means, thereby spacing said frame from the floor of said casing, an operating lever pivoted to the base of said frame, in the space therebelow determined by said boss means, an eccentric at the lower end of the armature shaft cooperating 65 with said lever, the forward end of said lever protruding through the front of said casing, a contact breaker in circuit with the field coil mounted on top of said armature frame and a cam formation at the upper end of the armature shaft for operating said contact breaker.

11. Apparatus of the character described, comprising an elongated insulating casing constituting a handle, a universal electric motor mounted therein and including a two-pole field structure fitted at its sides between the sides of said casing and secured therein, an energizing coil about the end of said field structure, a rotary armature, a carrying frame therefor, said frame fixed to the floor of said casing, a contact breaker including arms mounted on top of said motor carrying frame, said arms carrying contacts at the free ends thereof, said ends extending downward into the space between said field coil and said armature and between the legs of said field structure, the end of said armature shaft having a cam for operating the contact breaker.

12. Apparatus of the character described comprising an insulating casing, a universal electric motor mounted therein, said motor including a two-pole field structure fitting and secured in 20 said casing, an armature structure including a rotor and a carrying frame therefor, said frame affixed in said casing, a coil about said field structure, a contact breaker carried by said armature frame and means connecting said field coil 25 in circuit with said contact breaker, said means comprising a pair of wire holders fixed to said field structure, leads from said field coil held by said wire holder and flexible leads from the latter fixed at their opposite ends with respect 30 to said breaker contacts.

13. An armature structure for a universal motor comprising a series of magnetic iron laminations each presenting a plurality of poles, a shaft extending through said laminations, a carrying frame comprising a base and a cover plate turned inward into corresponding clearances in the extreme laminations for bearing mount of said shaft and spacer means securing said frame plates together in fixed spaced relation.

14. An armature for a universal motor comprising a stack of superposed laminations, each presenting armature poles and a concentric composite circular lamination constituting part of said stack, presenting armature poles, and intervening stiff non-magnetic segments, the elements of said stack being rigidly secured together.

15. Apparatus of the character described comprising an insulating casing constituting a handle, a universal electric motor therein, said motor comprising a field structure fitted in said casing, a rotary armature fixed in said casing between the poles of said field structure, said armature having a plurality of poles, means for imparting impulses in rapid succession for continuous operation of said rotor and means for starting said rotor, said latter means comprising a starting roller exposed through a corresponding port in said casing, and a rigid disk concentric with and constituting part of said armature and contacted by said starting roller when the latter is pressed inward.

16. Apparatus of the character described, comprising an insulating casing, a universal electric motor therein, said motor comprising a two-pole field with legs along the sides of said casing, a rotary armature structure including a carrying frame fixed in said casing, an armature rotor having bearings in said frame and including a plurality of poles and a hand starter for said armature, said starter comprising a small starting roller exposed through a corresponding port in said casing, said armature including a concentric rigid circular disk, adapted to be rotated by said starting roller, said disk including non-

magnetic segments between the poles thereof.

17. Apparatus of the character described, comprising an insulating casing, a universal motor therein comprising a two-pole field with legs 5 along the sides of said casing, an armature rotor between the poles of said field structure, said rotor having a metallic carrying frame, three bosses in the floor of said casing mounting said carrying frame, bearings for said rotor in said carrying frame, a contact breaker structure carried by said frame, a cam on the upper end of said rotor shaft for operating said contact breaker, leads from said field coil to said contact breaker, an operating lever in the space below said carrying frame determined by said bosses, said lever pivoted at 10 one end to said carrying frame, an eccentric at the lower end of the armature shaft for operating said lever, the forward end of said lever protruding through the front end of said casing, said armature having a plurality of spaced poles, starting means for said armature comprising a 15 starting roller exposed through a corresponding port in said casing, said armature including a rigid non-magnetic part between the poles adapted to be engaged and rotated by actuation 20 of said starting roller.

18. An automatic tool comprising a handle having an electric motor incorporated therein, and starting means for said motor comprising a 25 roller exposed at the exterior of the casing out of contact with the rotor, but adapted under pressure of the thumb to be brought into engagement with a part of said rotor for effective application of starting torque thereto.

33 19. In electric apparatus of the character described, an electro-magnetic coil structure comprising two coil units in contiguous relation, a breaker contact connecting said units in series, and an insulating plate separating said coils, 30 whereby said plate acts as the dielectric of a condenser, of which the coils are the electrodes, thereby to reduce arcing at said contacts.

20. In apparatus of the character described, a 35 motor including a stator and a rotor, said motor having an electro-magnetic coil, a contact breaker in circuit with said coil and including at least one contact movable relative to said coil, conductors electrically connecting said coil to said contacts, said conductors being flexible to accommodate relative movement and comprising 40 sheets of exposed metal of substantial width, each of length considerably greater than the distance between the ends thereof and free from contact with the structure at the major part of the length thereof and serving as heat dissipating fins.

21. An automatic tool comprising a handle casing having incorporated therein an electric motor including a rotor, a manual starting device comprising a roller accessible from the exterior of the casing, and exposed to be brought into 5 starting torque-applying coaction with the rotor by pressure of the finger thereagainst, and means retaining the starting device out of contact with the rotor while the motor is running.

22. An automatic tool comprising a handle 10 casing having incorporated therein an electric motor including a rotor, a starting roller exposed at the exterior of the casing, said rotor having rigid non-magnetic segments between the poles thereof, at the region of the plane of said start- 15 ing roller.

23. An automatic tool comprising a handle casing having incorporated therein an electric motor including a rotor, a starting roller exposed at the exterior of the casing, said rotor having 20 rigid non-magnetic segments between the poles thereof, at the region of the plane of said starting roller, and means loosely retaining said roller free from contact with said rotor while the latter 25 is operating.

24. An automatic tool comprising an insulating handle casing having incorporated therein an electric motor including a rotor, a starting roller exposed through a port in the casing narrower than said roller, said rotor having a carrying frame and including rigid non-magnetic segments intervening between the rotor poles in the plane of the roller, said parts correlated with the roller to block the latter from dropping inward, said port exerting a friction hold on said 30 roller releasably to retain the latter out of engagement with the rotor.

25. A small electric motor comprising a field structure and an armature, an insulating casing enclosing the same having mounting means, a 40 tool exposed exteriorly of said casing at one end thereof, said casing having a lead inlet at the other end thereof, a transmission within said casing connected from said armature to said tool, said casing including complementary parts 45 comprising a base and a cover, said parts having contacting rims extending obliquely of the casing with the narrowest part of the cover near the tool end thereof, and the wider part of the cover at the lead inlet, said complementary cas- 50 ing parts having cooperating notches at their contacting rims to accommodate the inlet leads.

JOHN A. HANLEY.
